ABSTRACT OF THE DISCLOSURE

Apparatus for effecting and controlling the movement of a railway wagon on a railway track by means of a carriage mounted on a separate track for movement parallel to said railway track said carriage having at least one arm movable to and from an operable position for contact with a wagon on said railway track by means of a movable actuating member on said carriage wherein movement of said arm is effected frictionally by contact between a first friction surface on said actuating member and any part of a second friction surface extending parallel to said railway track. Said second friction surface may be a rail on which said carriage is movably supported.

This invention relates to devices for moving or controlling the movement of rail wagons and the like of the kind comprising a carriage adapted to be propelled on a track disposed parallel to the rails for the rail wagons and having arms adapted to be moved into or out of the path of the wagons to propel said wagon or control its movement such device being hereinafter referred to as "a device of the kind described."

In devices of the kind described various arrangements have been proposed for effecting the movement of the arms automatically by the change in tension of the hauling rope or chain for example so that the provision of separate power source is avoided. In our prior U.K. Patent No. 714,598 the carriage was mounted on skids and use was made of the resistance to movement of the carriage due to the friction of the skids on the track to cause the tension in the haulage rope or chain to actuate the mechanism for moving said arm actuating mechanism.

According to the present invention there is provided a device of the kind described wherein the mechanism on said carriage for moving said arm or arms includes a movable member adapted to engage a complementary fixed member arranged along the path of said carriage. The engagement between the fixed and movable members may be frictional and may consist in the provision of friction pads carried on one or more of the arms so that the forces of friction act directly thereon and in this way the movement of the arms into or out of the path of the wagon is effected by movement of the carriage on its track and consequently is independent of the tension in the hauling rope or chain for propelling the carriage.

Referring to the accompanying drawings:

FIG. 1 is a diagrammatic plan view of one form of device made in accordance with the present invention in which the upper half of the top plating has been removed;

FIG. 2 is a side elevation of the device shown in FIG. 1;

FIG. 3 is an end view of the device, shown in FIGS. 1 and 2;

FIG. 4 is a section on the line IV—IV of FIG. 1;

FIG. 5 is a part sectional view of the friction member assembly shown in FIG. 1;

FIG. 6 is a diagrammatic fragmentary plan view of a modified form of device made in accordance with the present invention showing the arms in the projected position;

FIG. 7 is a view of the mechanism illustrated in FIG. 6 showing the arms in the withdrawn position;

FIG. 8 is a part sectional elevation of one of the friction members embodied in FIG. 6;

FIG. 9 is a section on the line IX—IX of FIG. 6;

FIGS. 10 and 11 are part plan and sectional elevation respectively of a modified form of movable member assembly.

15 In the form shown in FIGS. 1 to 5 the device comprises a fabricated sheet metal carriage body 2 of roughly rectangular shape in plan at the four corners of which are brackets 4 in which are mounted flanged wheels 6 shown supporting the carriage 2 on rails 8. The frame of the body 2 is of roughly I shape having end wheel carrying transverse beams 10 joined by a central longitudinal beam 12 of box section provided with diagonally arranged transverse members 14 between which the sides of the longitudinal beam 12 are cut away to provide 20 apertures 16 on both sides through which a single pivoted arm 18 projects said arm being mounted centrally in the longitudinal beam 12 on a fixed pivot pin 20 (FIG. 4) secured in the top and bottom members of the box section. The arm 18 is of box section provided with a central boss 22 which is journaled on the pin 20 and carries one member of a thrust ball bearing 24. The arm 18 is capable of a small axial movement on the pin 20 being supported by a spring 26. As will be seen from FIG. 5 the right hand end of the arm 18 carries a pair 25 of brackets 28 between which is mounted a lever 30 on a pivot pin 31 secured in the brackets 28. At the free end of the lever 30 is mounted a circular friction pad 32 positioned over the rail 8 and large enough in diameter to maintain contact with the rail 8 at all times during movement of the carriage. In the example shown the pad 32 is held pressed onto the rail 8 by a compression spring 34 acting between the pivoted arm 18 and the lever 30 (FIG. 5). A stop 36 on the body 2 limits the 30 pivotal movement of the arm 18 which is shown in chain line in FIG. 1 against said stop this being the withdrawn position of the arm 18 indicated in chain lines. The pivoted arm 18 is provided with upper and lower rollers 38 and 40 the upper being adapted to contact a wagon wheel 42 indicated diagrammatically in FIG. 2 whilst 35 the lower rolls on the rail 44 of the wagon wheel track. The arc described by the friction pad 32 is indicated by the chain line 46. For the propulsion of the carriage body 2 a shock absorber assembly 46 is shown secured to the rear end thereof for attachment thereto fore and aft of a haulage line (not shown) any convenient form of shock absorber may be employed so long as it provides the desired amount of yield to smooth out any normal shocks which may occur when the wagon wheels are engaged.

40 50 55 60 65 70 75 80 85 90 95 100 In operation as the carriage body 2 is hauled in either direction the friction between the pad 32 and the rail 8 will swing the arm 18 about the pin 20 either to extend the arm 18 to the position shown in full lines in FIG. 1 when moved to the right or to the withdrawn position shown chain dotted when hauled to the left. In the extended position the upper rollers 38 will engage a wagon wheel as shown in FIG. 2 and the wagon can be propelled by the hauling means. Obviously the pivotal movement of the arm 18 will provide a balance of the propelling force on the two wheels engaged by the rollers on the two arm ends.

Turning now to FIGS. 6 to 9 it will be seen that instead of a single pivoted arm 18 there are two substantially identical pivoted arms 60 mounted on the fixed pin 20 these arms 60 being linked together and to a roller 62 by links 64 said roller 62 being positioned loosely in a guide 66. In the form illustrated two friction pads 32 are provided, one on each arm but owing to the linkage one pad would suffice. The play between the roller 62 and the guide 66 allows the propelling force on the wagon to be balanced between the two arms. A stop 68 on the longitudinal beam 12 limits the extension of the arms 60 and a transverse plate 70 provides a limit stop for the withdrawn position of the arms 60 shown in FIG. 7. The operation of this modified form is functionally the same as described with reference to FIGS. 1 to 5.

FIG. 8 is almost identical with FIG. 5 and FIG. 9 with FIG. 4 and the appropriate reference numerals have been added to the figures.

In the modified form of movable member assembly illustrated in FIGS. 10 and 11 there is provided at the free end of the pivoted lever 30 a cubic block 70 of sufficient weight to provide the pressure required. The block 70 is turnably carried on a pin 72 mounted on the arm 30 transversely to the fixed rail, and is provided with a friction pad 32 for alternative use on each of four of its faces not traversed by pin 72. The block 70 is provided with four drilled and tapped holes 74 on each of the faces traversed by the pin 72 for engagement by locking screws 76 which are inserted through correspondingly positioned holes in the arm 30. With this construction should excessive wear occur to that pad 32 which is in frictional contact with the beetle rail 8 the screws 76 can be removed and the block 70 turned to present another pad 32 and the screws 76 re-engaged.

What we claim and desire to secure by Letters Patent is:

1. A railway wagon control apparatus comprising, in combination,
 a carriage mounted for movement parallel to the path of a wagon,
 a movable arm mounted on said carriage for movement into and out of the path of a wagon,
 a movable actuating member on said carriage,
 a connection between said member and said arm, and
 a first friction surface on said member for contact 45 with a second friction surface arranged parallel to said wagon path.

10
15

2. Apparatus according to claim 1 in which said movable actuating member is supported on said movable arm.

3. Apparatus according to claim 1 in which said movable actuating member is yieldingly supported on said movable arm.

4. A railway wagon control apparatus comprising, in combination,

a carriage,
 a track for said carriage arranged parallel to the track for the wagon to be controlled thereon,
 a movable arm mounted on said carriage for movement into and out of the path of said wagon,
 a movable actuating member on said carriage,
 a connection between said member and said arm,
 a first friction surface on said movable actuating member,
 a contact member mounted parallel to and extending along said track for operable engagement by said movable actuating member where control is to be effected, and
 a second friction surface on said contact member for engagement by said first friction surface.

5. Apparatus according to claim 4 wherein said contact member is one of the rails of the track on which said carriage is supported.

6. A railway wagon control apparatus comprising, in combination,
 a carriage arranged to be propelled on a track,
 a railed track disposed parallel to rails on which railway wagons are movably supported,
 two movable arms on said carriage movable into or out of contact with a railway wagon on said rails,
 a friction linkage joining said arms, and
 a member on each said movable arms each positioned for engagement with said railed track on which the carriage is supported.
